UNITED STATES PATENT OFFICE.

SILAS LEE OWEN TAYLOR, OF HUNTINGTON, WEST VIRGINIA, ASSIGNOR OF ONE-
THIRD TO MOTIE LUTHER RUSSELL, ONE-THIRD TO CHARLES C. TAYLOR, AND ONE-
THIRD TO J. W. HENSLEY, ALL OF HUNTINGTON, WEST VIRGINIA.

COMBINED LEVELING AND PLUMBING IMPLEMENT.

1,242,740.

Specification of Letters Patent.

Patented Oct. 9, 1917.

Application filed June 30, 1916. Serial No. 106,811.

To all whom it may concern:

Be it known that I, SILAS LEE OWEN TAYLOR, a citizen of the United States, residing at Huntington, in the county of Cabell and State of West Virginia, have invented certain new and useful Improvements in Combined Leveling and Plumbing Implements, of which the following is a specification.

This invention relates to combined leveling and plumbing implements, and has for one of its objects to simplify and improve the construction and increase the efficiency and utility of devices of this character.

Another object of the invention is to provide a simply constructed implement which may be employed as a plumbing or leveling implement, as a support for a flexible element coacting with the plumbing portion and which may also be graduated to serve as a tapeline, and likewise containing a foldable carpenter's square, or like implement also coacting with the plumbing portion of the implement, the various devices being so disposed that they do not interfere with each other or with the ordinary uses of the implement.

With these and other objects in view, the invention consists in certain novel features of construction, as hereinafter shown and described and then specifically pointed out in the claims; and in the drawings illustrative of the preferred embodiment of the invention—

Figure 1 is a vertical front elevation, partly in section, of the improved implement;

Fig. 2 is an edge view of the same;

Fig. 3 is a view enlarged of a portion of the body of the implement including one of the plumbing devices, with the cover removed;

Fig. 4 is a section on the line 4—4 of Fig. 3;

Fig. 5 is a section on the line 5—5 of Fig. 1;

Fig. 6 is an enlarged side elevation of a portion of the body at one end illustrating the arrangement of the folding "square" portion of the device;

Fig. 7 is a bottom plan view of the portion shown in Fig. 6 with the swinging blade of the square in section on the line 7—7 of Fig. 6;

Fig. 8 is a perspective view from beneath of

a portion of the swinging blade portion of 55 the square;

Fig. 9 is a detached perspective view from above of the swinging blade locking member;

Fig. 10 is a detached perspective view of 60 the guard plate associated with the swinging blade portion of the device;

Fig. 11 is an enlarged sectional detail on the line 11—11 of Fig. 6.

Corresponding and like parts are referred 65 to in the following description and indicated in all the views of the drawings by the same reference characters.

The improved implement comprises a body portion, represented as a whole at 10, 70 and preferably of wood, of the ordinary size or dimensions of a conventional spirit level, but may be of other sizes and material if preferred.

Near one end a cavity is formed in the 75 body 10 to receive a casing 11, preferably circular, and in which a stud 12 is mounted for rotation and provided with an operating handle, represented conventionally at 13, externally of the casing 11 and of the body 10. 80 The operating handle 13 is preferably foldable and preferably of the form usually employed in connection with ordinary tape-line reels.

A receiving drum 14 is connected to the 85 stud 12 and partakes of its rotation. Embedded within the adjacent end of the body 10 is a socket 15 which communicates through a passage 16 with the interior of the casing 11 and is preferably provided 90 with guide rollers 17. Connected at one end to the drum 14 is a flexible member 18 preferably in tape form and extending through the passage 16 and between the rollers 17 and is provided with a pull ring or loop 19 95 which is received within the socket 15 when the flexible member is entirely rolled upon the drum, as illustrated in Fig. 1. Thus no part of the flexible member extends beyond the casing 10 when the latter is in rolled or 100 withdrawn position. The member 18 may be graduated to serve as a tapeline, if preferred. Formed within the body 10 and opening through one side, and preferably intermediate its ends, is a recess or cavity, represented conventionally at 20, while a similar cavity is formed in the end of the body 10 opposite to the casing 11 of the flexible mem- 105

- ber 18. The intermediate cavity 20 and the corresponding terminal cavity, the latter not being shown in detail, are designed to receive and support plumbing devices, and as the plumbing devices are precisely alike the description of one will suffice for both.
- Located within the recess 20 and against its inner face is a metal plate 21, preferably circular and provided with a plurality of 10 graduations, indicated at 22, and preferably formed upon a projecting ledge or flange 23, the latter being semi-circular in outline, or extending from the upper half of the plate 21. Attached to the plate 21 is a centering member 24, and likewise attached to the plate is a bracket device 25 having a centering socket in alignment with the centering socket of the member 24. The centers of the members 24-25 are preferably formed of 15 refractory substance substantially the same as employed in watches and clocks and designated "jewels." Engaging in the centers or "jewels" of the members 24-25 is a short shaft or pin 26, the member 26 being thus arranged to vibrate or rotate in the 20 "jewels" as centers, whereby the friction is materially reduced. Extending from the shaft member 26 is a pointer 27 which is thus caused to move in close proximity to the 25 graduations 22. Extending from the shaft 30 member 26 at the side opposite the pointer is a counterbalance device 28, as large and heavy as possible, and which operates to maintain the pointer in vertical position.
- A clamp screw 29 operates through the bracket member 25 and is designed to engage the weight 28 and hold the latter and the pointer 27 in stationary position when required, as hereafter more fully explained.
- A cover member, represented as a whole at 30, is embedded within the face of the body 10 externally of the cavity 20 and is provided with an opening in the upper side 35 adapted to receive a transparent body 31, such as glass and through which the position of the pointer relative to the graduations is readily discernible. The graduations may be of any required number, but will preferably be arranged to denote the more commonly used degrees of a circle, and may be of any required number and spaced any required distance apart. The glass covered opening is preferably greater than one-half of the cavity 20, so that the range of movement of the pointer is sufficient to indicate when the body 10 is in exact horizontal or exact perpendicular position and at numerous intermediate points. When the implement is to be used as a level, the intermediate indicator or plumbing device will be employed, and when the implement is to be used for plumbing the indicator device at the upper end of the body will be employed either alone or in coaction with the flexible element 18. When the member 18 is thus employed it may be provided with a weight or "plumbbob," not shown.
- Embedded in the face of the body 10 at one end is a blade 32 which is preferably graduated in the same manner as the longer 40 arm of a carpenter's square, and formed in the body 10 adjacent to the blade 32 is a relatively long cavity or recess 33. A shorter blade, represented as a whole at 34, is provided with an offset portion 35 which engages beneath one end of the blade 32 and is pivotally connected thereto at 36. The pivot 36 extends through the adjacent portions of the blades 33-34 and is received at its inner end, as shown at 37, in a locking member, represented as a whole at 38. Depending from the offset portion 35 of the blade 34 are holding ribs 39 spaced apart and arranged in pairs, two pairs of the ribs being generally employed as shown in Fig. 85 8. The upper face of the member 38 is formed with a square groove 40 into which the inner or adjacent pair of the ribs 39 engage, while the outer rib members engage over the outer face of the member 38. The 90 channels 40 correspond in length to the ribs 39, and the blade 34, is, therefore, adapted to be disposed in two positions relative to the member 38. Thus when the blade 34 is disposed in parallel relation to the blade 32 95 the inner pair of ribs 39 will engage in the channels 40 which extend transversely of the body 10, and when the blade 34 is disposed at right angles to the blade 32, as shown in Fig. 6, the inner pair of the ribs 39 will engage in the channels 40 which extend longitudinally of the body 10. The member 38 is arranged to be moved away from the blades 32 and 34 and within a recess 41 in the body 10 and against the resistance of a 100 spring 42 within the recess as illustrated in Fig. 11. The projecting portion of the pivot pin 36 also serves as a push button whereby the member 38 may be depressed against the resistance of the spring 42 to detach the channels 40 from engagement with the ribs 39, thus releasing the blade 34 and permitting it to be rotated upon the pin 36 in changing its position. Thus when the blades 32-34 are to be disposed in parallel 105 relation, as shown in Figs. 1 and 2, pressure is applied to the combined push button and pin to depress the locking member and separate the channels 40 from the ribs 39 and permit the blade 34 to be correspondingly 110 depressed until the body of the latter blade is below the lower line of the blade 32 when the blade 34 can be readily rotated upon its pivot to either one of its two positions as will be obvious. When either one of the 115 two positions is thus reached the reaction of the spring 42 will lock the blades 32-34 together and retain them in whatever position they may be placed. The body 10 is preferably provided with a plumb line, rep- 120 125 130

resented at 43, and in alinement longitudinally of the terminal pointer 27 and the line of movement of the flexible element 18 when the pointer 27 is in parallel relation 5 to the side edges of the body 10 and of its line 43.

When thus arranged, the movable blade 34 when disposed in its outer position, will coact with the pointer and flexible element 10 to accurately denote the right angled position of any body. Either of the pointers 27 may also be employed in coaction with the flexible element 18 and the graduations 22 to denote any required angular position of 15 the body 10.

A compass, shown conventionally at 45, is embedded in the body 10. The recess 41 is preferably inclosed by a guard plate 44.

The improved implement is simple in construction, can be inexpensively manufactured and of any required size.

Having thus described the invention, what is claimed as new is:

1. In a device of the class described, a body having a longitudinally directed recess, a stationary blade attached to the body and forming one side of said recess, and a movable blade swinging relative to said stationary blade and adapted to be seated in 30 said recess when in one position, said movable blade having an off-set and a stop shoulder coacting with the stationary blade to hold the movable blade positively in extended position relative to the stationary blade. 35

2. In a device of the class described, a body having a longitudinally directed recess, a stationary blade attached to the body and forming one side of said recess, a movable 40 blade swinging relative to said stationary blade and adapted to be seated in said recess

when in one position, said movable blade having an off-set and a stop shoulder coacting with the stationary blade to hold the movable blade positively in extended position relative to the stationary blade, and a locking device spring supported, and operating to hold said movable blade positively in open position and yieldably in withdrawn position. 45

3. In a device of the class described, a supporting body having a longitudinally directed recess, a blade stationary with said body and forming one side of said recess, a blade pivoted to swing relative to said 50 stationary blade and having stop ribs extending in spaced relation, a locking member having sockets at right-angles to each other, one set of said sockets adapted to receive the stop ribs when the movable blade 55 is in withdrawn position and the other set of said sockets to receive the stop ribs when the movable blade is in extended position, and means for holding said locking member in engagement with said stop ribs. 60

4. In a device of the class described, a supporting body, a stationary blade attached to said body with one edge in alinement with one edge of the body, a blade movable relative to the stationary blade and 70 having stop ribs, a locking member spring supported and having a plurality of sockets to receive said stop ribs when the movable blade is in different positions and hold the same, and a pin connected to said locking 75 member and extending through said blades and forming pivotal connection between the same, said extension beyond the stationary blade adapting the same to be compressed to actuate the locking member. 80

In testimony whereof I affix my signature.
SILAS LEE OWEN TAYLOR. [L. S.]
